UNITED STATES PATENT OFFICE.

CHARLES A. KUSTER, OF NEW YORK, N. Y., ASSIGNOR TO BILTMORE LIGHTING FIXTURE CO., A COPARTNERSHIP, OF BROOKLYN, NEW YORK.

DESIGN FOR A BACKPLATE FOR A LIGHTING FIXTURE.

Application filed November 20, 1924. Serial No. 11,416. Term of patent 7 years.

To all whom it may concern:

Be it known that I, CHARLES A. KUSTER, a citizen of the United States, and a resident of the borough of Queens, Queens county, city and State of New York, have invented a new, original, and ornamental Design for a Backplate for a Lighting Fixture, of which the following is a specification, reference being had to the accompanying drawing, forming a part thereof.

Fig. 1 is a side elevation; and
Fig. 2 is a front view of a backplate for a lighting fixture showing my new design.

I claim:

The ornamental design for a backplate for a lighting fixture, as shown.

CHARLES A. KUSTER.
